FRANK E. WATTS AND DONALD T. HASTINGS, OF DETROIT, MICHIGAN, ASSIGNEES, BY
MESNE ASSIGNMENTS, TO HUPP MOTOR CAR CORPORATION, OF RICHMOND, VIR-
GINIA, A CORPORATION OF VIRGINIA.

ENGINE-CASING.

1,225,088.

Specification of Letters Patent.

Patented May 8, 1917.

Application filed October 21, 1915. Serial No. 57,155.

To all whom it may concern:

Be it known that we, FRANK E. WATTS and DONALD T. HASTINGS, citizens of the United States of America, residing at Detroit, in the county of Wayne and State of Michigan, have invented certain new and useful Improvements in Engine-Casings, of which the following is a specification, reference being had therein to the accompanying drawings.

The invention relates to explosion engines and more particularly to engines of the V type.

The invention resides in an arrangement of the valve stems and actuating members therefor, which will permit ready access to these parts; in the novel construction and arrangement of the valve actuating members; in the provision of a valve actuating mechanism which will insure the valve operating members remaining in proper contact with the driving cams therefor when the engine is running at high speed, and which will avoid a detrimental pounding between the valves and their seats; in the novel arrangement of the exhaust passages; in the novel arrangement of the valve chambers; and in certain combinations of parts and details of construction as will more fully hereinafter appear.

In the drawings,—

Figure 1 is a perspective view of an engine embodying the invention;

Fig. 2 is a cross-section therethrough;

Fig. 3 is a side elevation thereof.

A designates the crank case, B and C the opposed cylinder casings arranged upon opposite sides of the crank case, forming what is known as the V-type of engine, the particular structure herein shown being an eight cylinder engine. The V-type of engine increases the width of the upper portion of the engine casing, and in order to minimize the width of the engine casing at the top, it is desirable to arrange the valves and the actuating mechanism therefor on the inner sides of the cylinders. It is also desirable to position a portion of the accessories within the space between the opposed cylinder casings, as this not only further condenses the parts but also positions the accessories so that they are readily accessible. However, with engines having the general arrangement of parts just described now in

quite common use, the accessories when positioned between the opposed cylinder casings, prevent ready access to the actuating mechanism for the valves so as to adjust such mechanism. We have therefore, so constructed and arranged the valves and the actuating mechanism therefor that these parts are readily accessible.

In the one embodiment of the invention, the valves D for each of the cylinders has the stem E thereof mounted for reciprocation in a substantially horizontally-arranged bearing F. G is the crank shaft, H the cam shaft driven therefrom in any well known manner, and I are rockers having bearings J journaled upon a shaft K arranged parallel to the cam shaft H. Each of the rockers has an arm L provided with a bearing M for engaging a cam N on the cam shaft, while the other arm O on the rocker carries an adjustable bearing P that contacts with the outer end of the valve stem E. The laterally-extending valve stems and the rockers are arranged within chambers Q on the inner side of the cylinder. In the particular structure illustrated there are two of these chambers for each set of cylinders and the induction conduit R has the branches S thereof connected to the cylinders between these chambers (see Fig. 1). The chambers Q are so constructed as to provide free access to the parts contained therein, as by forming the chambers with a detachable cover T. Furthermore with the arrangement shown, the chamber is formed by a section U that is detachably connected to the cylinder casing as by bolts V. The chambers Q are however, sufficiently restricted in width to permit the carburetor W, magneto X, or other accessories, to be arranged between the chambers of the opposed cylinder casings. As will be readily seen upon reference to the drawings, the parts arranged between the chambers Q do not prevent free access being had to such chambers.

Each of the valves D—which are of the puppet type—is held to its seat by a spring A'. If this spring was employed to return the valve to its seat and also to hold the bearing M of the rocker in engagement with the actuating cam, it would have to be of considerable tension. Particularly is this so if the motor is adapted for high speed. But it is objectionable to place the spring

¹⁰ A' under considerable tension, as it will subject the valve and its seat to a detrimental hammering. We therefore, employ a separate spring B' which acts upon the rocker to hold the bearing M in engagement with the actuating cam. Our novel arrangement not only permits the use of a comparatively light tension spring for closing the valve, thereby reducing the wear between the valve and its seat to a minimum, but also permits the valve parts to be made comparatively light. A further advantage lies in the fact that the spring B' at all times holds the bearing M in contact with the ¹⁵ cam, eliminating any tendency for pounding action between these parts. In order to permit the valves to be engaged with their seats, the outer face of the engine casing is provided with openings C' of a sufficient size to permit the valve to be inserted there-through into engagement with its seat. These openings are closed by a screw-threaded plug or cap member D'.

²⁰ To produce the best efficiency for high speeds it is desirable to have the path of the gas from the valve chamber *a* to the cylinder as direct as possible, and with the arrangement of valve and valve chamber shown, a very direct passage from the valve chamber *a* to the cylinder is had, and this passage is comparatively free from bends or turns.

²⁵ As before stated, in the V-type of engine it is desirable not to arrange any parts on the outside of the cylinder casings, for this would increase the width. However, if the exhaust manifold is arranged adjacent the tops of the cylinder casings and upon the inner sides thereof, they tend to prevent free access to the parts between the cylinder casings. Furthermore, if the exhaust manifolds communicate with the engine casings adjacent the top, they must pass rearwardly of the end of the casing. Such an arrangement in motor vehicles causes the exhaust pipe to be so positioned as to materially heat the foot-board, producing an objectionable heating of the forward inclosure, especially in the summer or warm months. We have ³⁰ therefore, so positioned the exhaust that it will not be subject to these objections. Thus the exhaust branches F' G' of each of the cylinder casings lead from the inner face thereof to a common conduit or trunk I' which has a portion extending downwardly between the pairs of cylinders and terminating in a discharge end J', then passes out of the cylinder casing on the side of the latter, but beneath the upper portion of the cylinder casing. This does not in any way increase the width of the casing, as will be seen upon reference to Fig. 2. Also such an arrangement allows the portion of the exhaust conduit that is attached to the end ³⁵ J' to be positioned a considerable distance

from the foot-board and thereby eliminates the tendency of the manifold to objectionably heat the forward inclosure.

As the exhaust branches F' G' and the trunk I' are in effect inclosed within the cylinder casing, it is necessary to amply cool these parts. To this end a comparatively large water-jacket and chamber K' is formed around the trunk I' and the branches F' G'. These chambers communicate directly with ⁷⁵ the branches L' of the water conduit.

From the foregoing description it will be readily appreciated that an engine casing is provided which allows of highly condensing the parts and still permits ready access to the accessories arranged between the opposed cylinder casings and to the adjustable parts of the valve-actuating mechanism.

While we have shown and described a very desirable form of the invention, we do ⁸⁵ not wish to limit the protection to the particular structure illustrated, but consider the invention to be of sufficient scope to embody various modifications.

What we claim as our invention is:—

1. In a V-type of engine, the combination with the opposed cylinder casings, valves therefor, stems for the valves arranged on the inner side of the cylinder casing, and an adjustable means between the valve stems and said actuating mechanism positioned adjacent the top of said cylinder casing, and spaced chambers respectively associated with said cylinder casings within which said adjustable means is arranged, said chambers ⁹⁵ having removable portions providing access to said means.

2. In a V-type of engine, the combination with the opposed cylinder casings, valves therefor, a substantially horizontal stem for each valve positioned adjacent the upper end of the casing, a rocker adjacent the lower end of the casing, a journal for said rocker, said rocker being provided with an arm, an adjustable bearing carried by said arm and engaging the end of the valve stem, and said rocker having a second arm, a cam shaft, and a cam on said shaft for actuating said second arm.

3. In a V-type of engine, the combination with the opposed cylinder casings, exhaust conduits for each of said casings communicating with the cylinders upon the inner sides thereof, said exhaust conduit terminating in a discharge end positioned upon the outer side of said cylinder casing.

4. In a V-type of engine, the combination with the opposed cylinder casings, exhaust conduits for each of said casings communicating with the cylinders upon the inner sides thereof, said exhaust conduit terminating in a discharge end positioned upon the outer side and arranged beneath said cylinder casing.

5. In a V-type of engine, the combination

- with the opposed cylinder casings, the exhaust conduits of each of said casings communicating with the cylinders upon the inner sides thereof, said exhaust conduit being 5 inclosed within the cylinder casing and terminating in a discharge end positioned upon the outer side of said cylinder casing, and a comparatively large water-jacketing chamber surrounding said conduit.
- 10 6. In a V-type of engine, the combination with the opposed cylinder casings, of exhaust conduits for each of said casings communicating with the cylinders upon the inner sides thereof, said exhaust conduits being 15 inclosed within the cylinder casing and terminating in discharge ends positioned upon the outer side of the respective cylinder casings, comparatively large water-jacketing chambers surrounding said conduit, and a water inlet conduit communicating directly with each of said chambers.
- 20 7. In a V-type of engine, the combination with separately formed opposed cylinder casings, exhaust conduits for each of said casings communicating with the cylinders upon the inner sides thereof and cast integral with the respective casings, and a comparatively large water-jacketing chamber surrounding each of said exhaust conduits.
- 25 8. In a V-type of engine, the combination with separately formed opposed cylinder casings, exhaust conduits for each of said casings communicating with the cylinders upon the inner sides thereof and cast integral with the respective casings, each of said exhaust conduits terminating in discharge ends positioned upon the outer side of the corresponding cylinder casing, a 30 comparatively large water-jacketing chamber surrounding each exhaust conduit, and a water inlet conduit communicating directly with each water-jacketing chamber.
- 35 9. In a V-type of engine, the combination with the opposed cylinder casings and crank case, of valves for said casings, stems for the valves arranged on the inner sides of said casings, a cam shaft within the crank-casing, and rockers pivoted adjacent the junctures 40 of the cylinder casings and crank case, each having a substantially vertical arm for engaging a valve stem and an arm extending inwardly to the cam shaft.
- 45 10. In a V-type of engine, the combination with opposed cylinder casings of a puppet valve in each of said casings, laterally extending stems for said valves arranged adjacent the upper ends of said casings, a rocker coacting with each of said stems, each of said rockers having an upwardly extending arm adapted to engage the outer end of the associated valve stem, and spaced chambers respectively associated with the opposed cylinder casings, within each of which the outer end of one of said valve stems and the arm engaging the same are arranged, each of said chambers including a removable closure. 55 60 65
11. In a V-type of engine, the combination with a crank casing having oppositely inclined faces, of detachable opposed cylinder casings mounted thereupon, each comprising a lower cylinder portion and an upper housing portion, said portions being seated respectively upon the upper and lower portions of one of said inclined faces, valves carried by said cylinder casings, a valve actuating member within the crank-casing, and mechanisms respectively in said housings transmitting motion from said 70 75 80 valve actuating member to the valves.
12. In a V-type of engine, the combination with an inclined cylinder, of a housing integral therewith, said cylinder and housing forming a detachable unit, a substantially horizontal valve rod carried by said unit, valve actuating rockers carried by said unit, a support for said rockers within said housing, and springs within said housing tending to displace said rockers from the 85 90 95 valve rods.
13. In a V-type of engine, the combination with a crank-casing, of an inclined cylinder detachably mounted upon said crank-casing, a bell crank mounted upon said cylinder having an arm exterior to the crank-casing and an arm projecting into the crank-casing, a valve actuatable by the exterior arm, and actuating means within the crank-casing engaging the arm projecting 100 into the same.
